Inventor:

William A. Hunter,
by Oscar Middleton Donaldson, his
Atty's.

UNITED STATES PATENT OFFICE.

WILLIAM A. HUNTER, OF TERRE HAUTE, INDIANA, ASSIGNOR TO DELLA R. HUNTER,
OF TERRE HAUTE, INDIANA.

VEHICLE-TOP.

1,231,892.

Specification of Letters Patent.

Patented July 3, 1917.

Application filed April 27, 1916. Serial No. 93,942.

To all whom it may concern:

Be it known that I, WILLIAM A. HUNTER, a citizen of the United States, and resident of Terre Haute, Indiana, have invented cer-
5 tain new and useful Improvements in Ve-
hicle-Tops, of which the following is a speci-
fication.

10 My present invention relates to improvements in top constructions for vehicles, and
more especially of the rigid or non-folding
type.

15 The invention has among its objects to se-
cure an extremely economical, light and rigid
construction, which will maintain its shape
in service and be free from all liability to
bag or wrinkle, and the invention includes
20 the novel features hereinafter described and
particularly defined by the appended claim.

An embodiment of my invention is illus-
25 trated in the accompanying drawing, in
which,

Figure 1 is a sectional elevation of a suffi-
cient portion of a top to show the application
of the covering material to the supporting
25 frame, and,

Fig. 2 is a side elevation.

Referring by reference characters to this
drawing, the numeral 1 designates the side
rail of the vehicle top and 2 the bows.
30 These may be of the ordinary or any desired
form, being usually constructed of wood, and
being supported from the vehicle body by
standards, which as they form no part of the
present invention, are not shown herein.

35 To the curved portions of the bows on
each side, I apply a panel or stiff cover re-

taining member 3, which may consist of sheet
metal, card-board, or wood veneer.

The panel is secured in place by nailing
or tacking it to the bows and also securing 40
its lower edge to the side rail in a similar
manner.

I preferably, before the panel is secured in
place, apply to its inner face a covering 4 of
a material corresponding to the lining or in-
terior face of the waterproof cover, such
covering being cemented to the inner face
of the strip or panel 3 and having a portion
4^a extended beyond the inner edge of the
strip. 50

The waterproof covering is indicated at 5
and before this is applied a cushion or pad
6 is placed upon the surface of the panel or
strip 3 and the extended edge 4^a is turned
back over the padding and preferably ce- 55
mented to the upper surface thereof.

The waterproof covering 5 being then se-
cured in position in the customary manner,
it will be seen that it is supported in a nicely
rounded position at the curved part, all sag- 60
ging is prevented, and yet the interior has a
neat fabric-lined appearance, throughout.

What I claim is:

In a vehicle top the combination with the
cross bows and outer cover, of curved strips 65
or panels of rigid material interposed be-
tween said cross bows at the curved portions
thereof, and lining material covering the
inner faces of said panels and folded over
the inner edges thereof and lying between 70
the cover and outer faces of the panels.

WILLIAM A. HUNTER.
